United States Patent Office

Des. 203,435
Patented Jan. 11, 1966

203,435

INFANT'S TRAINING CHAIR

James F. Sellars, Jr., ½ Hamilton Cosco, Inc., Columbus,
Ind., and Reynold C. King, P.O. Box 2339, Prescott,
Ariz.

Filed Mar. 19, 1965, Ser. No. 84,354

Term of patent 3½ years

(Cl. D4—5)

FIG. 1.

FIG. 2.

FIG. 3.

FIG. 4.

FIG. 5.

FIG. 1 is a side elevation of an infant's training chair showing our new design;

FIG. 2 is a front elevation thereof;

FIG. 3 is a plan view thereof;

FIG. 4 is a rear elevation thereof and showing a receiving vessel in dotted lines; and

FIG. 5 is a plan view thereof but showing the lid in raised position.

The dominant features of our invention are shown in full lines.

We claim:

The ornamental design for an infant's training chair, as shown and described.

UNITED STATES PATENT OFFICE

Certificate

Patented January 11, 1966

Patent No. D. 203,435

James F. Sellars, Jr. and Reynold C. King

The United States District Court for the Northern District of Ohio, Eastern Division, having, pursuant to Title 35, Section 256 of the United States Code, ordered that the above identified United States patent be corrected by adding the name of Raymond R. Spilman as a joint inventor, it is this 10th day of February 1970, certified that the name of the said Raymond R. Spilman is hereby added to the said patent as a joint inventor with the said James F. Sellars, Jr., and Reynold C. King.
